UNITED STATES PATENT OFFICE.

JOHN T. DRUFVA, OF LONGMEADOW, MASSACHUSETTS, ASSIGNOR TO HENRY HYMAN & CO. INC., OF NEW YORK, N. Y., A CORPORATION OF NEW YORK.

PORTABLE ELECTRIC LIGHT.

1,320,846.

Specification of Letters Patent.

Patented Nov. 4, 1919.

Application filed December 22, 1917. Serial No. 208,346.

To all whom it may concern:

Be it known that I, JOHN T. DRUFVA, a citizen of the United States, and a resident of Longmeadow, in the county of Hampden and State of Massachusetts, have invented certain new and useful Improvements in Portable Electric Lights, of which the following is a specification.

The invention pertains more particularly to the character of electric flash lights to be held in the hand and lighted, as occasion may require, by the manual movement of a slide applied upon the exterior casing of the device.

15 My invention resides more particularly in a novel arrangement and construction of parts, including means for completing the circuit between the lamp and battery, which obviate the accidental circuiting of the lamp 20 by contact with metal articles, such as might arise when a flash light, otherwise constructed, is placed in a box of tools.

The flash light of my invention comprises an exterior casing, a plural cell battery 25 therein, a thumb-piece or slide on the side of the casing, means on the movement of said slide for completing the circuit between the lamp and battery, a metal sleeve applied upon the upper end of the casing and holding 30 the lens and binding the same against the reflector, a lamp bulb of customary type held by the reflector and engaging the positive pole of the battery and a novel support within the outer end of the casing to receive 35 the sleeve of the reflector and comprising a ring to set within the casing, an insulating disk held in said ring and serving to insulate the reflector from adjacent metal parts of the casing and a metal plate at the bottom of 40 said insulating disk in electrical connection with the sleeve of the reflector and affording a surface to be engaged by a conductor to be placed in circuit by the manual actuation of the slide on the exterior of the casing.

45 My invention is applicable to flash lights having metal casings, which in themselves serve as a conductor, and also to flash lights having fiber casings, this latter class of flash lights usually having conducting strips extending 50 between the negative pole of the battery and the lamp and to be placed in circuit with each other by the manual movement of a spring-switch connected with a thumb-piece on the side of the casing.

55 The invention will be fully understood

from the detailed description hereinafter presented, reference being had to the accompanying drawings, in which:

Figure 1 is a central longitudinal section, with the wrapping on the battery partly broken away, of a portable flash light embodying my invention, the casing of the flash light in this instance being of metal;

Fig. 2 is a detached top view of the support I arrange within the outer end of the casing to receive the lower or sleeve-portion of the reflector;

Fig. 3 is a central vertical section, on a larger scale, through the parts of the aforesaid support, the insulating disk and its immediate features being shown as separated from the encompassing ring and ready to be dropped thereinto;

Fig. 4 is a view corresponding with Fig. 1, but illustrating a flash light of the "Miner" type and having a fiber or insulating tubular casing;

Fig. 5 is a detached vertical section through the fiber casing and is presented to illustrate, more particularly, the circuit conductors extending between the ends of the casing and carried by said casing;

Fig. 6 is a sectional view through the upper portion of a flash light showing a modified construction of the support for the reflector, in this instance the support and reflector being connected together so as to be handled as one piece;

Fig. 7 is a top view, on an enlarged scale, of a modified form of the support for the reflector, this support being of the character I employ in very small flash lights;

Fig. 8 is a sectional view through the same, taken on the dotted line 8-8, of Fig. 7;

Fig. 9 is a vertical section through the upper portion of a flash light embodying my invention, the construction shown in Fig. 9 being one I employ in instances in which the battery and the outer casing may be disproportionate, one to the other, in length, and

Fig. 10 is a detached top view of the support, shown in Fig. 9.

In the drawings, referring to Figs. 1, 2 and 3, 10 designates a tubular metal casing, 11 a plural cell battery therein, 12 a wrapping of insulating material on said battery, 13 a screw-cap of customary construction closing the lower end of said casing, 110

14 a conducting spring compressed between the negative pole of the battery and the inner surface of said cap, 15 a sleeve screwed upon the outer end of said casing, 16 a customary lens held by said sleeve, 17 a reflector within the outer end of the casing 10 and out of electrical contact therewith, and 18 an electric bulb of known character having its terminal sleeve 19 screwed into the usual threaded sleeve 20 at the inner end of said reflector, the other terminal 21 of the lamp being held in engagement with the positive pole 22 of the battery by means of the spring 14. Near the outer end of the casing 10 said casing is enlarged laterally, whereby about in line with the lower end of the reflector 17, an annular shoulder 23 is created, and upon this shoulder is seated a metal ring 24, shown on an enlarged scale in Fig. 3, comprising an upper annular portion 25 which engages the shoulder 23 with a snug fit, a lower annular portion 26 which projects downwardly slightly into the upper portion of the casing 10 below said shoulder, 25 and a horizontal flange 27 which extends inwardly from the lower edges of said annular portion 26.

A disk 28 of insulating material and carrying a bottom plate or disk 29 of conducting material is seated within the ring 24 and therewith forms a support for the reflector 17. The disk 28 and disk 29 are secured together by an eyelet 30 down into which the sleeve 20 of the reflector 17 projects, and the said sleeve and eyelet are in electrical contact, the upper edge of the eyelet being against the lower portion of the reflector surrounding its said sleeve. The metal disk 29 is smaller than the insulating disk 28, as clearly shown in Fig. 3, and when the disk 28, with the disk 29, is seated within the ring 24, the disk 29 is insulated from said ring by reason of the fact that its outer edge is separated or sets inwardly from the inner edge of the flange 27 of said ring. The disk 28 serves to support the disk 29 and being of insulating material, the disk 29 normally remains out of electrical connection with the ring 24 and also with the exterior casing 10. In assembling the parts the disk 28, carrying the disk 29, is seated within the ring 24 and therewith introduced through the upper end of the casing 10, the said ring becoming seated on the shoulder 23, as shown in Fig. 1. The reflector and lamp may then be applied to position, and thereafter the lens is secured against the upper edges of the reflector by means of the sleeve 15. The sleeve 15 serves to hold the lens 16 against the reflector and also to keep the reflector in constant electrical connection with the eyelet 30 of the support formed by the disks 28, 29, eyelet 30 and ring 24.

Upon one side of the casing 10 is provided

a slide 31 which is secured to an inner conducting strip 32 by means of eyelets 33, which enter slots formed in the casing 10 so that the slide 31 and strip 32 may have sliding movement imparted to them by the user of the flash light. In Fig. 1 I illustrate the slide 31 and strip 32 in their outer position completing the circuit through the lamp and battery, the upper end of the strip 32 being bent inwardly so that when said strip is moved to its outer position, the bent end, which I number 34, of the strip, will pass into electrical contact with the disk 29, which, as we have already explained, is, through the eyelet 30, in electrical connection with the sleeve of the reflector. The strip 32 is of thin brass, and when moved to its outer position the bent end 34 thereof may be pressed with spring effect against the disk 29 and thereby assure positive electrical connection between said strip and said disk. When the slide 31 is moved downwardly from its position shown in Fig. 1, it will carry the strip 32 downwardly and break the connection between the upper end of the strip and the lower surface of the disk 29, thus breaking the circuit and extinguishing the light.

In Figs. 4 and 5 I illustrate my invention as applied to a lamp of the "Miner" type, and therein 35 designates a fiber tubular casing, 36 a plural cell battery therein, 37 a wrapping of insulating material on said battery, 38 a screw cap of customary construction closing the lower end of said casing, 39 the customary conducting spring between the bare lower end of the battery and the inner surface of said cap, 40 a shell screwed upon the upper end of the casing 35 and bent inwardly near the upper end of said casing to form an annular shoulder 41, 42 the reflector, 43 the lens, 44 a sleeve formed at the lower portion of said reflector and into which said terminal 46 is screwed and which extends through the eyelet 48 of the support formed by the insulating disk 49 carrying the metal disk 50. The disk 49 is within a metal ring 51 which is seated on the shoulder 41, and said disk 49, ring 51 and conducting disk-plate 50 are identical in construction with the reflector supporting members shown in Figs. 1, 2 and 3, and therefore do not require more specific description. The purpose of presenting Figs. 4 and 5 is to illustrate how the supporting members, shown in Figs. 2 and 3, may be successfully employed in a "Miner" type of flash light having a fiber casing. The lower terminal 52 of the lamp is in contact with the pole 53 of the battery, as usual.

Within the casing 35 are two normally separated conductor strips 54, 55, the lower end of the strip 54 being in electrical connection with the negative pole of the battery, 5 and the upper end of the strip 55 being in electrical connection with the contact disk 50 carried by the insulating disk 49. The inner end of the strip 54 is in electrical connection with an escutcheon 56 secured upon 10 the exterior of the casing 35, and the inner end of the strip 55 is secured to the casing 35 by an eyelet whose outer end is exposed within said escutcheon; and partly within said escutcheon is arranged a switch 57 to be 15 manually operated from the exposed head thereof and which, when in one position, through the member 58 thereof, electrically connects the strip 55 with the escutcheon, and therefore establishes electrical communication 20 between the strip 55, escutcheon 56 and strip 54, for making the circuit. When the switch 57 is slid downwardly from the position in which it is shown in Fig. 4, the member 58 thereof leaves its electrical 25 connection with the lower or inner end of the strip 55, and at that time the circuit becomes broken and the lamp extinguished. In the position of the parts shown in Fig. 4 the circuit is completed through the lamp. 30 In the construction shown in Fig. 1, there being a conducting casing 10, I employ the slide 32, for the purpose of making and breaking the circuit, while in the construction shown in Fig. 4 I employ the switch 57 35 to complete the circuit between the inner ends of the strips 54, 55, the upper end of the strip 55 being in constant engagement with the conducting disk 50.

The construction shown in Fig. 6 is identical with that illustrated in Fig. 1, except that I flange the lower edge of the sleeve 20 of the reflector outwardly, as at 59, so as to fasten the supporting members 24, 28, 29, 30, to the reflector, and this construction is 40 advantageous in that it permits the reflector and its said supporting members to be handled as one piece, and further this construction assures the electrical connection of the reflector with the conducting disk 29 at 45 all times. The construction shown in Fig. 6 will, therefore, be understood without further explanation.

In Figs. 7 and 8 I illustrate a form of the reflector-supporting means which is employed in very small lamps, and therein 55 60 denotes the metal ring, 61 the insulating disk, 62 the conducting disk carried thereby and 63 the eyelet which connects the disks 61, 62 and serves to receive the sleeve portion 65 of the reflector. The ring 60 is indented at its upper edges, as at 64, to project over the edge of the disk 61 and thereby aid in retaining said disk on a shoulder 65 formed within the ring 60 by an inwardly projecting annular beading, the shoulder 65 performing the

function of the flange 27, shown in Fig. 3. The disk 61, disk 62 and eyelet 63 correspond with the like features shown in Fig. 3. The ring 60 has its shoulder 65 formed by an inwardly projecting annular beading, and below said beading the ring 60 has a skirt portion 66 which projects downwardly into the casing of the flash light. The essential features of the construction shown in Figs. 7 and 8 correspond with the reflector-supporting features, shown in Figs. 1 to 3 inclusive.

In Figs. 9 and 10 I illustrate a flash light employing the essential features shown in Fig. 3 in the same tubular casing 10 shown in Fig. 1, and having the same sleeve 15, lens 18, reflector 17 and lamp-bulb 18 illustrated in Fig. 1, but the reflector-supporting means shown in Fig. 9 are adapted to occupy a sometimes unusual space left between the positive pole 22 of the battery and the lower terminal 21 of the lamp-bulb in instances in which the length of the battery and the length of the casing 10 may be disproportionate to each other.

In Figs. 9 and 10 the reflector-support comprises the metal ring 67, which corresponds with the ring 24 shown in Figs. 1, 3 and 6, and engages a shoulder 23 on the casing 10, the insulating disk 68 and metal disk 69, said disks 68, 69 being the same as the disks represented in Fig. 3. In the construction shown in Fig. 9 the disks 68, 69 are secured together by an eyelet 70, which is formed upon the upper end of a downwardly extending tube 71 into the upper end of which the lamp sleeve 19 projects. Near its lower end the tube 71 has an inwardly bent beading 72 which creates a shoulder against which an insulating washer 73 abuts. The washer 73 encompasses a contact cup 74 which engages the positive pole 22 of the battery and receives in its upper portion a vertically movable cap 75 containing a coiled spring 76, the spring having a bearing on the lower end of the contact 74 and against the upper end of the cap 75 and operating to press the cap 75 against the terminal 21 of the lamp so as to form an electrical connection between said terminal and the positive pole of the battery. The tube 71 and contact members 74, 75, 76 are employed in cases in which the battery may be too short for the casing 10, or the casing 10 too long for the battery. The reflector supporting members, shown in Figs. 9 and 10, are the same as the reflector supporting features presented in the other figures of the drawings, but in addition to said features in this instance the tube 71 and members associated therewith are made use of, while the same features are not required in a construction such as shown in Fig. 1 or in Fig. 6, because the casing and battery there shown are proportionate to each other. In the

construction shown in Figs. 9 and 10, the upper edge of the cup contact 74 is flanged inwardly and the lower edge of the cap 75 is flanged outwardly, thereby forming stops 5 which prevent the separation of said parts 74, 75. I also show the ring 67 as indented inwardly at 77, so as to aid in securing the fiber disk 68 and metal disk 69 in position within the ring 67.

10 The invention will be understood from the foregoing description without further special explanation. The circuit is made through the lamp and battery by the movement of the slide 32 against the disk 29, the 15 casing 10 being of conducting material and extending from the negative pole of the battery. In the construction shown in Figs. 4 and 5 the casing is of fiber, and hence the circuit must be made and broken by means 20 of the switch 57 and metal strips 54, 55. In each instance the construction is such as to prevent the accidental lighting of the lamp, as by the placing of the flash-light in a box of tools. The construction has been designed 25 both for convenience of manufacture and to avoid the accidental lighting of the lamp. The construction is one convenient of manufacture, since the parts may be readily made and assembled and, when assembled, perform their duties efficiently.

30 What I claim as my invention and desire to secure by Letters Patent, is:

1. In a flash-light having a casing, reflector, lens, lamp bulb and battery, said 35 casing having adjacent to its forward end a shoulder and said lens being secured over the reflector by an exterior ring, in combination, a supporting member for said reflector, comprising a metal ring adapted to 40 engage said shoulder, an insulating disk fitted within and supported by said ring, a metal plate on the lower side of said disk, a metal eyelet connecting said disk and plate and receiving the lower tubular portion of 45 said reflector, and means for connecting the negative pole of the battery with said metal plate, one terminal of the lamp being in electrical connection with the positive pole of the battery, and said reflector at its upper 50 edge being spaced from the surrounding metal parts of the flash-light.

2. In a flash-light having a casing, reflector, lens, lamp bulb and battery, said lens being secured over the reflector by an exterior 55 ring, in combination, an insulating disk supported in the forward end of the casing, a metal plate on the lower part of said disk, a metal eyelet connecting said disk and plate and receiving the lower tubular portion of 60 said reflector, means for connecting the negative pole of the battery with said metal plate, and a vertically yieldable contact carried by said disk and engaging one terminal of the lamp and being in electrical 65 connection with the positive pole of the bat-

tery, said reflector being supported by said disk and plate and at its upper edge spaced from the surrounding metal parts of the flash-light.

3. In a flash-light having a casing, reflector, lens, lamp bulb and battery, said lens being secured over the reflector by an exterior ring, in combination, a supporting member for said reflector supported in the forward end of the casing, comprising a 70 metal ring, an insulating disk fitted within and supported by said ring, a metal plate on the lower side of said disk, a metal eyelet connecting said disk and plate and receiving the lower tubular portion of said reflector, and means for connecting the negative pole of the battery with said metal plate, one terminal of the lamp being in electrical connection with the positive pole of the battery, and said reflector at its upper 75 edge being spaced from the surrounding metal parts of the flash-light.

4. In a flash light having a casing, reflector, lens, lamp bulb and battery, said lens being secured over the reflector and said reflector having a depending tubular portion receiving the lamp, in combination, a supporting member for said reflector supported adjacent the forward end of the casing, comprising a metal ring, an insulating disk fitted 90 within and supported by said ring, a metal disk at the lower face of said insulating disk and at its edges spaced from the conductive surfaces of the flash-light, and means for connecting the negative pole of the battery with said metal disk, one terminal of the lamp being in electrical connection with the positive pole of the battery and said reflector at its upper edge being 95 spaced from the surrounding metal parts of the flash-light and at its lower tubular portion being extended through said disks and in electrical connection with said metal disk.

5. In a flash-light having a casing, reflector, lens, lamp bulb and battery, said lens being secured over the reflector and said reflector having a depending tubular portion receiving the lamp, in combination, a supporting member for said reflector supported adjacent the forward end of the casing, comprising a metal ring, an insulating disk fitted 110 within and supported by said ring, a metal disk at the lower face of said insulating disk and at its edges spaced from the conductive surfaces of the flash-light, and means for connecting the negative pole of the battery with said metal disk, one terminal of the lamp being in electrical connection with the positive pole of the battery and said reflector at its upper edge being 115 spaced from the surrounding metal parts of the flash-light and at its lower tubular portion being extended through said disks and flanged outwardly and being in electrical 120 connection with said metal disk.

6. In a flash-light having a casing, reflector, lens, lamp bulb and battery, said lens being secured over the reflector and said reflector having a depending tubular portion receiving the lamp, in combination, a supporting member for said reflector supported adjacent the forward end of the casing, comprising a metal ring, an insulating disk fitted 125 within and supported by said ring, a metal disk at the lower face of said insulating disk and at its edges spaced from the conductive surfaces of the flash-light, and means for connecting the negative pole of the battery with said metal disk, one terminal of the lamp being in electrical connection with the positive pole of the battery and said reflector at its upper edge being 130 spaced from the surrounding metal parts of the flash-light and at its lower tubular portion being extended through said disks and flanged outwardly and being in electrical connection with said metal disk.

6. In a flash-light having a metal casing, reflector, lens, lamp bulb and battery, said lens being secured over the reflector and said reflector at its upper edge being spaced from the surrounding metal parts of the flash-light and at its lower portion having a depending tubular member receiving the lamp, in combination, a support for said reflector adjacent the forward end of the casing, comprising a metal ring, an insulating disk fitted within said ring, a metal disk at the lower face of said insulating disk and at its edges spaced from the conductive surfaces of the flash-light, means connecting the negative pole of the battery with said casing, an external slide on said casing, and an inferior conductive strip connected with said slide and having a forward end adapted to engage said metal disk when moved so to do, one terminal of the lamp being in electrical connection with the positive pole of the battery, and the tubular portion of said reflector being extended through said disks and in electrical connection with said metal disk. 20 25
- Signed at Springfield, in the county of Hampden and State of Mass., this 20th day of December, A. D. 1917.
